UNITED STATES PATENT OFFICE.

ERSKINE RAMSAY, OF BIRMINGHAM, ALABAMA.

SAMPLER MECHANISM.

1,249,491.

Specification of Letters Patent. Patented Dec. 11, 1917.

Application filed October 2, 1916. Serial No. 123,445.

To all whom it may concern:

Be it known that I, ERSKINE RAMSAY, a citizen of the United States of America, residing at Birmingham, in the county of 5 Jefferson and State of Alabama, have invented certain new and useful Improvements in Sampler Mechanism, of which the following is a specification.

My invention relates to mechanism which 10 is adapted for both sampling and checking cars of coal or other mineral in order that an accurate record may be obtained of the character and quality of the mineral loaded by the different miners or loaded into different freight cars.

In Letters Patent No. 1,191,227, issued to me on the 18th day of July, 1916, I have shown and described a mechanism for sampling and checking miners' coal by means 20 of a reciprocable and rotatable sampling pocket which is movable crosswise of the chute in order to take a sample at any desired point transversely of the stream of mineral and which may be timed to take 25 the sample at any time during the dumping of the mine car. By this means it was possible to obtain a small but truly average sample of each car and such sample when withdrawn from the chute was delivered to 30 a bin which may comprise, if desired, a plurality of sample holding pockets and beneath is arranged a screening mechanism which separated the slack from the lump and enabled the lump portion of the sample 35 to be more quickly and thoroughly picked for slate or rock as it passed over the screen during the screening operation. The subdivided slack, lump and slate of each sample were delivered to separate receptacles and 40 their contents respectively weighed and entered upon a tally sheet, each sample being designated by the number of the miner's check on the car from which taken. The record showing the proportion of lump and 45 slack, made possible by the use of the screen and the same being recorded upon a tally sheet, gives a record on each miner and shows whether he is unnecessarily breaking the coal and therefore producing an excessive 50 amount of slack with its usual high proportion of foreign matter. This point is very important at mines generally and especially

at those endeavoring to produce the highest possible proportion of lump and domestic coal.

My present invention has for its purpose to improve the structure of the patented apparatus with a view to simplifying it, to broadening its adaptability to tipples of varying construction, and to adapting it to 55 take in rapid succession truly average samples of a whole trip of cars if desired, no matter how quickly dumped, and to preserve the samples separately for their subsequent treatment over a single screen at the 60 leisure of the operator.

My improved sample taking mechanism comprises the arrangement of a transverse series of sample pockets each below a hole in the tipple chute bottom and each having 70 an individual movable cover so that the sample may be taken in any desired pocket. The several sample pockets are adapted to deliver their samples under control of their respective discharge valves through a common feed chute to a common shaking screen. The relative location of the pocket transversely of the chute determines from what 75 part, laterally of the stream of mineral flowing from the car, the sample will be 80 taken, and the movable covers provide means for taking the sample from the early or any later part of the stream. The sample pocket covers are manually and independently controllable through levers which are in convenient reach of the operator in charge of 85 the screening and picking operation, thus permitting one man to take entire charge of the sampling operation and enabling him to vary at will both the place and time of taking the sample so as to prevent the mine 90 cars being with undue amounts of slate in a part of the car which otherwise would not be sampled and the miner thus avoid detection.

The further feature of my present invention relates to the manufacture of the whole sampling apparatus as a single structure which can be fabricated and delivered complete to the mine where the only change required is the cutting of the necessary opening in the tipple chute bottom above the pockets and the provision of a guard plate to receive the falling mineral from the mine 95 100

car and protect a pocket cover when retracted thereunder to expose a pocket for taking a sample.

A further improvement relates to the provision of a signal to automatically notify the man on the tipple when a sample is being taken so that he can notify the sampler of the miner's check number, or, as is preferable, send down through a chute or on a rod the miner's check or a special check of corresponding number for the car being sampled, which check may be hooked or attached, first, to the lever for opening the discharge valve of the pocket in which the sample was taken, and, later, to the boxes containing the screened and picked sample to properly identify the latter until entered upon the tally sheet. The check when attached to the lever thus also constitutes an indicator to the sample man of which pockets are full. Screen bars of regular or irregular distances apart may be arranged over each or any number of the sample pockets so that they will exclude therefrom all lumps above predetermined sizes, this being often desirable where the mineral, and particularly the coal as mined and loaded, often comprises very large lumps. Such lumps would not be a fair portion of an average sample and might also easily enter and choke the pocket and interfere with the closing of its cover unless such lumps are caused to pass over the pocket by the screen bars. Where the run of mine mineral is small these bars may be partially or entirely dispensed with, or they may be regularly or irregularly spaced any desired distance apart in any pocket or pockets, but where used they are of such character and so constructed as to enable the cover to easily force off any lumps, that might hang on the screen, without becoming blocked thereby.

These and other advantages will be better understood by reference to the more detailed description hereinafter and to the accompanying drawings which form a part of this specification, and in which what I regard as the preferred embodiment only of my invention is illustrated; it being understood that the details of construction may be widely varied without departing from the real substance of my invention.

According to the drawings:

Fig. 1 is a side elevation of a mine tipple structure equipped with my sampling apparatus.

Fig. 2 is a side elevation of the sampling apparatus enlarged with the tipple chute partly in section and the sampler pockets broken away.

Fig. 3 is an elevation looking away from the tipple.

Fig. 4 is a section on the line 3-3 of Fig. 1.

Fig. 5 is a front elevation looking toward

the tipple partly broken away to illustrate one of the adjustable pocket bottoms.

Fig. 6 is a detail view of the chute for delivering the miners' checks from the tipple level to the sampling platform.

Similar reference numerals refer to similar parts throughout the drawings.

In the embodiment of my invention illustrated in the drawings, a mine car 1 is shown in dumping position on a tipple 2 with the mineral falling therefrom upon a guard plate 3 raised above the bottom 4 of the coal chute 5. The guard plate 3 is connected at its sides to angle bars 6 which are fastened to the side walls of the chute. The bottom 4 of the chute, beginning at a point below the lower end of the guard plate 3, is cut away to form a rectangular transverse elongated opening through which the mineral is intended to fall into the sampling apparatus disposed thereunder. The transverse upper and lower edges of the opening in the chute being of substantial length are reinforced beneath by transverse angle bars 7 which extend from side to side of the chute and these angle bars are riveted to upper ends of the front plate 8 and the back plate 9 forming respectively what I term the front and back walls of the sampling apparatus. At their outer ends these angle bars 7 are connected to vertically disposed angle bars 10 riveted to the sides of the chute. End plates or walls 15 are connected to the walls 8 and 9 to form the outer casing of the sampling apparatus and four intermediate vertically disposed partitions 11 extend lengthwise of the chute and divide the sampling casing into five sampling pockets, equal in size and each pocket having an individual bottom discharge door 12 which is hinged to the back wall 9 and held in closed position against the front wall 8 by a counterweight 13 on the lever 14 for manually operating the discharge door. The side walls 15 extend downwardly in parallelism to a point below the level of the discharge doors 12, where they are bent inwardly to form a hopperlike feeder chute 16 adapted to receive a sample from any one of the several sample pockets and deliver it to a shaking screen 17. The back wall 9 is inclined upwardly away from the wall 8 so that the sample pockets increase in size toward their upper ends. A square door 18 is hinged in the back wall 9 with its bottom corner edges projecting beyond the tapering bottom end of the chute 16 and the door has drag teeth 19 which depend almost to the level of the shaker screen 17. A counterweight 20, mounted on the arm 21 that is attached to the door 18, serves to yieldingly hold the door against the mineral so as to distribute it gradually over the shaking screen. The bottom of the screen below the

chute 16 is solid, thus forming a reciprocating feeder for the screen, and the mesh wire screen extends therefrom to the lower end of the screen. The lower end of the plate 8 extends sufficiently below and to each side of the bottom end of the chute 16 to form gusset plates 22 and to each of these plates is attached a depending angle bar 23 which bars support the front end of the frame 24 for the sample bins under the screen, the rear or other end of this frame-work being supported by two angle bars 25 connected by means of gusset plates 26 to the upper end of the plate 9.

I provide a sliding pocket cover 27 for each sample pocket, these covers being preferably made of sections of channel bars, inverted and adapted to slide in angle guides 28 attached to the upper edge of each side wall of the several pockets. As illustrated in Fig. 4, a convenient manner of attaching these angles is by bending over the upper edge of the partitions 11 and side walls 15 to an angle of 45° and riveting or otherwise fastening the angle guide thereto. By this arrangement the several covers are held in contiguous relationship so as to form a sectional closure for the transverse opening in the chute bottom 4. The upper end of each pocket cover carries a yoke 28^a to which is pivoted a link 29 which in turn is pivotally connected to the upper end of a lever 30 for operating the pocket cover. Each cover is controlled by a separate lever and the several levers are mounted to rock on a common shaft 31 mounted in bearings 32 which are each supported by angle bars 33 and 34. Each angle bar 34 is connected to a gusset plate 26 and each angle bar 33 is connected by a gusset plate 35 to an angle bar 25 and by a gusset plate 36 to the back wall 9 of the sampling apparatus. Each lever has riveted thereto a gusset plate 37 and a half pipe flange 38 is bolted to this gusset plate, a hole being bored through the plate in line with the opening in the flange which is bored smooth, thus affording a rocking bearing for the lever. The several levers are spaced by pipe sleeves 39 interposed between their rocking bearings. The handle ends of the levers are disposed in convenient position to be operated from the platform 40 which is suitably supported from the tipple frame-work. The frame 24 for the sample bins may be additionally braced by the tie bars 41 and 42 which connect to convenient points in the tipple frame-work and are respectively made fast to the gusset plates 43 and 44. This frame 24 is formed of longitudinal and transverse angles suitably bolted to form a rectangular frame from which depends a hopper divided transversely by inclined partitions to form three distinct sample bins 45, 46 and 47. The bin 45 receives slack coal or screened mineral and is disposed beneath the screen 17; the bin 46 is disposed to receive the lump coal or mineral that falls off the end of the screen; and the end bin 47 is intended to receive the lump slate or rock picked from the mineral on the screen or in the hopper 46. The slack bin 45 has a balanced butterfly valve 48 in its bottom forming its discharge door and provided with an angle stop lug 49 to prevent it swinging quite to a vertical position. This valve swings on a bearing 50 which is offset from the center to make it self closing by gravity. An angle bar 51, attached to the free end of the valve, extends on each side beyond the hopper and in position to be depressed by the foot or hand to open the valve. The bin 46 has a bottom door 52 which swings on a hinge 53 and is held normally closed by a counterweight 54. This door also carries at its free end an angle bar 55 which projects sufficiently to enable it to be engaged by the foot or hand to open the door. The bin 47 has a vertically hinged end door 56 held normally closed by a counterweight 57 on a hand lever 58 which projects in convenient position to be grasped and raised to dump the bin. Below the bins 45, 46 and 47, respectively, are arranged containers, 59, 60 and 61, respectively, for the treated sample, which are suitably marked to indicate their respective contents.

The screen 17 is mounted on flanged wheels 62 journaled on the frame 24 and angle bars 23 and disposed to incline the screen. A connecting rod 63, formed by a bent metal strap, is connected to the lower end of the screen and extends forward above the frame 24 to a crank shaft 64 journaled in bearings 65 attached to the angle bars 23. This shaft extends sufficiently on each side of the apparatus to attach to a shaft or to receive a driving pulley 66 on whichever side proves most convenient for connecting its driving belt to the line shaft or motor on the tipple.

It being desirable to reduce the results of the sampling operation to percentages for convenience in tabulating the results, I prefer to take samples of a predetermined weight, as, for instance, in sampling coal, I would design the pockets for an average capacity of samples about one hundred pounds, but it would seldom be exactly one hundred pounds. Therefore the actual total weight would be increased or reduced to a hundred pounds basis and the pounds of slack coal and slate being also changed in proportion would then also be the per cent., in which case comparisons would easily be made and averages struck. To make the pocket capacity variable for different mineral, I provide the discharge door 12 with an end plate 67 and a series of holes are punched in both

the door and plate, preferably on different centers, so that the plate can be adjusted toward or from the front wall 8 and held in such adjusted positions by the bolts 68. Obviously, this arrangement permits the close in positions at different angles to a horizontal plane and the wider the angle the greater the pocket capacity and vice versa.

In many cases it may be desirable to provide screens to prevent large lumps choking the pockets or to exclude from the sample mineral above a predetermined size. To these ends I may provide over each pocket, if desired, a series of screen bars 69. The ends of these bars are bent down and fitted between the front and back plates 8 and 9 and attached thereto by bolts passing also through the angle bars 7 so as to easily adjust the number or distances apart to suit the conditions desired for any pocket or of any mine. Additional holes are provided in the bars 7. These bars project sufficiently above the chute bottom 4 to permit lumps that may catch between them to be pushed off easily by the covers 27 as they are moved to closed position. In order that the man on the tipple may be advised when a sample is taken so that he can promptly send down the miner's check to the sample man or otherwise notify him of its number, I provide a gong 70 of ordinary construction, adapted to be rung by the depression of a spring retracted arm 71 which is connected by a pull rope, chain or wire 72 that passes over pulleys and across above the levers 30, being made fast at its end to a fixed member 73. A vertical rope, chain or wire 74 connects 72 with each lever and a pulley 73^a is disposed between each pair of ropes or wires 74. The pull rope 72 extends up and connects to the crank 75 that will rock nearly to initial position a signal plate 76 suitably marked to indicate that a sample is being taken.

To facilitate the delivery of miners' checks from the tipple platform to the sampling platform, I provide, as a preferred arrangement, a tube 79 which extends from the upper tipple floor level to a point in convenient reach of the sample. A guide rod or wire 80 for the checks is passed down through the tube 79 and at its lower end rests on an angle bracket 81 attached to and projecting below the lower open end of the tube. The checks, in the order that the cars are dumped, are strung on the rod 80 and work down through the tube till they rest on the platform on the bracket 81 and the sampler in practice removes them in order from the bottom of the stack and mounts them on the pins or hooks 78 on the levers 14 to identify by the miners' checks the samples taken in the pockets.

In operation, the pocket covers normally stand in closed position and thus do not in-

terfere with the normal use of the chute. When a sample is to be taken, the sample man observes the car as it tilts and at the desired time during the discharge of the mineral, he grasps and pulls down the lever 30 which will open the sample pocket at the desired point transversely of the flowing mineral. The lumps ride over the screen bars and the pocket fills, after which the lever 30 is thrust back up thereby forcing its cover to closed position. The manipulation of the lever notifies the tipple man and he sends down the tube 79 to the sample man the miner's check 77 which is hung on a pin 78 on the weight 13, where it serves as a notice that the pocket opposite it is full and identifies the sample therein. If the cars are dumped in trips, as many as five samples can be taken of different cars as rapidly as they can be dumped.

After the samples have been taken, they can be screened and picked at the convenience of the sample man. This is done as follows:—A lever 14 is raised to open a pocket discharge door 12 and drop the contents of a pocket into the screen feeder chute 16, the check being at the same time detached from the weight on the lever operated. The sample falls on the solid bottom or feeder of the inclined screen and is spread by the door 18 and fingers 19 into a thin mass and is fed by the reciprocating plate onto and passes over the screen bottom. The slack as separated by the screen falls into the bin 45, the lump into bin 46, and the picked slate is thrown by hand into bin 47. The sample boxes 59, 60 and 61 are arranged under the bins and at the completion of the screening and picking operation, the discharge doors of the bins are opened and their contents delivered into the boxes which are either then weighed and the results entered on the tally sheet opposite the check number of the sample, or they can be set aside with the check to mark them and later weighed up.

It will be obvious that the size and number of the sample pockets may be varied as desired and that the other details of construction which are disclosed merely in their preferred embodiment may be changed to meet different operating conditions without departing from the substance of this invention. It being noted as a special feature of my present construction that the control of the sampling mechanism is such as to make it possible to select a sample from any desired part of the contents of the car, thus obviating the possibility of the car being loaded by the miner in such manner as not to make the sample representative of the whole contents of the car.

What I claim as new and desire to secure by Letters Patent, is:—

1. Mechanism for taking representative

- samples of a moving stream of mineral, comprising a multi-ported bed over which the mineral stream flows, separate gates for the bed ports, which are disposed out of alignment with each other in the direction of the movement of the material, a sample chute under the bed, and selective means manually controllable and operable to set the gates to collect the sample through any desired port.
2. In a sampling mechanism, a plurality of sample pockets, a plurality of separate means operable at different points transversely of the stream of mineral to be sampled to direct part thereof into a predetermined pocket.
3. In a mineral sampling mechanism, a series of sample pockets arranged transversely of and disposed in the path of the moving body of mineral to be sampled, and door means operable at different points transversely of the stream of material to be sampled to admit portions of the material to any desired sample pocket or pockets.
4. In a sampling mechanism, a series of separate sample pockets having movable doors disposed across the path of the moving material to be sampled, and means to independently open and close said doors to take a sample in any desired pocket.
5. In a sampling mechanism, a series of separate sample pockets having movable doors disposed transversely across the path of the moving material to be sampled, and manually controllable means to independently open and close said doors to take the sample in any desired pocket and at any desired time during the movement of the body of material to be sampled.
6. A sampling mechanism comprising a chute having a plurality of transversely arranged sample pockets, and door means to open at will any desired pocket and admit thereinto a sample of the material moving in the chute.
7. In a mineral sampling mechanism, in combination, a car tipple, a chute to receive the contents dumped from a car, a plurality of pockets arranged transversely under and opening overhead through the bottom of the chute, and independently controllable doors for admitting samples to and discharging them from pockets, substantially as described.
8. In a sampling mechanism, the combination with a tipple chute having an opening in its bottom, of a multi-compartment sampling mechanism disposed below said opening and comprising independently movable doors for the compartments, which doors, in closed position, form a closure for the opening in the bottom of the chute.
9. The combination with a tipple chute having a bottom opening, of a sampling structure having a flaring top subdivided into pockets and attached to the chute with the pockets in position under the bottom opening in the chute, movable covers for the pockets adapted, in closed position, to bridge the opening in the chute, and means to independently control the discharge of samples from the pockets, substantially as described.
10. A sampling mechanism comprising a structure adapted to be interposed in the path of the moving body of material to be sampled and comprising a plurality of sample pockets, closures for the pockets controllable to admit material to any desired pocket, a common chute into which the several pockets are adapted to discharge their contents, discharge doors for the pockets, and a single sample treating mechanism adapted to receive the material from any of said pockets through said chute.
11. The combination with a tipple chute having a bottom opening therein, of a fabricated structure bodily attachable beneath the chute and having separate pockets to receive the material which falls through the opening of the chute, door means to direct said material to any desired pocket, means to identify each sample taken in a pocket, and means to deliver the samples taken in the order desired to be treated, substantially as described.
12. In a sampling apparatus, a casing comprising in its upper portion a subdivided hopper and in its lower portion a chute, doors for controlling the discharge of material from the subdivisions of the hopper into the chute, doors for controlling the admission of material to the subdivisions of the hopper, bins to receive the treated sample from the screen, and a metallic framework tying all said parts together into a unitary structure, substantially as described.
13. In a sampling mechanism, a tipple chute having an opening in its bottom, sample pockets under said opening, a plurality of slide doors bridging the opening in the chute and each controlling the admission of material to one of the pockets, and separate levers for opening and closing said doors, substantially as described.
14. In a sampling mechanism having a plurality of sample pockets, covers for said pockets, a chute to pass the material to be sampled over said covers, screen bars for the pockets which project substantially above the bottom level of the chute level, and positive means to open and close the doors in the direction of the length of the screen bars, substantially as described.
15. Mechanism for taking representative samples of a stream of mineral, a hopper divided by vertical partitions in line with the movement of the material, V-shaped slide guides at the top edge of said partitions, inverted channel bars mounted to slide in said guides and to normally cover the hopper, means to pass the mineral stream over said

bars, and means to operate the bars, substantially as described.

16. In a sampling mechanism, a sample pocket, means to admit a sample thereto, 5 a hinged discharge door for the pocket adapted to abut against a straight pocket wall to close the pocket, and means to adjust the width of the door to change its point of engagement with said straight wall and vary 10 the capacity of the pocket, substantially as described.

17. In a sampling mechanism, the combination with a tipple comprising a car dump and chute, of mechanism controllable to take 15 a sample at will from the material dumped from a car, and means automatically operable with the taking of a sample to give a signal on the tipple.

18. A sampling mechanism, comprising se-

lective means to take a sample at the desired 20 point transversely of the falling material, and a signal operated contemporaneously with and by the sampling mechanism when adjusted to take a sample, said signal being adapted to notify the man on the tipple that 25 a sample is being taken.

19. In combination, a tipple and its chute, a plurality of sample pockets interposed in the path of the material dumped over the tipple, an independently controllable cover 30 for each pocket, and a common signal for the man on the tipple, and means to operate said signal by the opening of any one of the pocket covers, substantially as described.

In testimony whereof I affix my signature. 35
